CLAIM

The ornamental design for a paint can pourer, as shown and described.

DESCRIPTION

FIG. 1 is a perspective view of the paint can pourer showing my new design;

FIG. 2 is a front elevational view thereof;

FIG. 3 is a rear elevational view thereof;

FIG. 4 is a left side elevational view thereof; the right side elevational view being a mirror image of the view shown in this figure;

FIG. 5 is a top plan view thereof;

FIG. 6 is a bottom plan view thereof; and,

FIG. 7 is a cross-sectional view taken across section-indicating lines 7—7 of FIG. 1 and illustrates the configuration of the wall of the paint can pourer.

1 Claim, 3 Drawing SheetsFIG. 1.

FIG. 7.

FIG. 2.

FIG. 3.

FIG. 4.

FIG. 6.
